CRYSTALLIZING EVAPORATOR

Burton S. Hughes, Buffalo, N. Y., assignor to
Zaremba Company, Buffalo, N. Y., a corpora-
tion of Maine

Application April 10, 1937, Serial No. 136,172

9 Claims. (Cl. 159—45)

This invention relates to evaporating methods and apparatus particularly adapted for crystallizing substances out of aqueous solutions by removing part of the water through evaporation.

5 One of the methods heretofore known comprises subjecting a solution to heat, causing the solution to flow upwardly to cause crystals to become separated and suspended in the solution, and withdrawing and returning a portion 10 of the solution for reheating and retreatment. A general form of apparatus which has been employed for carrying out this type of method includes an evaporator body associated with an external heater for the solution and a pump for 15 withdrawing, circulating and returning the solution.

In the usual apparatus of this character boiling occurs in the tubes of the heater and in contact with the walls of the evaporator and crystals 20 are deposited in the heater tubes; the crystals obtained are of inferior size; and the capacity and output of the apparatus are materially reduced by the presence of incrusted crystals in the heater tubes and circulation pipes and by the necessity of frequent stopping for boiling 25 out to remove the incrustations.

One of the principal objects of my invention is to provide apparatus in which no boiling occurs in the heater tubes and in which there is 30 no deposit of crystals in the tubes, on the surface of the evaporator shell, or in the pipes connecting the heater and evaporator.

Another object of the invention is the provision of an evaporator method by which a solution, preliminarily heated, is so proportioned 35 to and mixed with a solution of a different temperature as to produce the deposit of crystals of large size and quantity.

Another object is the provision of an evaporator system in which the solution is circulated 40 and recirculated through the heater tubes and evaporator, the circulation system being hydrostatically balanced and its operation requiring only the amount of power necessary to overcome friction.

45 Another object is the provision of an improved method of and means for regulating the temperature and condition of the solution and maintaining a hydrostatic balance.

50 A further object is the provision of improved means for distributing the solution within the evaporator and effecting intimate mixing of the incoming solution with the contents of the evaporator, resulting in uniform ebullition without explosive spouting and spraying of the solu- 55

tion in the evaporator, thorough circulation within the evaporator, and the building up of crystals of large size out of contact with the walls of the evaporator shell.

5 My evaporating system or effect may be used singly or connected in series with other effects for operation in stages.

The method and apparatus which constitute my invention pertain to the arrangement, construction and operation of an evaporator system 10 or effect, whether used as a single unit or in multiple. For the sake of convenience and to avoid unnecessary duplication only a single system or effect is represented in the drawings.

15 The drawings illustrate a preferred form of the apparatus or system which constitutes a part of my invention and which is adapted for the carrying out of my improved method.

In the drawings:

20 Figure 1 is a vertical, sectional elevation of my apparatus embodied in a single effect evaporator. Figure 2 is a top plan view thereof. Figure 3 is an enlarged horizontal section taken on line 3—3, Figure 1.

25 Similar characters of reference indicate corresponding parts throughout the several views.

Generally speaking, my apparatus or system 30 comprises an evaporator 10, a heater 11 located beneath the evaporator and connected to the discharge of a pump 12, a suction pipe 13 connecting the evaporator with the suction of the pump, a return pipe 14 connecting the discharge side of the heater with the evaporator, means 35 within the evaporator for mixing the heated solution supplied by the pipe 14 with the solution contained in the evaporator 10 and provision for free upward and downward circulation of the solution within the evaporator.

40 The heater 11 may be of any suitable form or type of construction. The structure illustrated is conventional, consisting of a heating chamber 15 containing a nest of heater tubes 16, the tubes being connected at their respective ends with an inlet chamber 17 in communication with the discharge of pump 12 and a discharge chamber 18 from which the heated solution is led, by the pipe 14, to the evaporator 10. The heating of the solution circulated through the tubes 16 is effected by steam, hot vapors or other suitable heating medium in the heating chamber 15. This heating chamber is provided with the usual steam inlet 19 and condensate outlet 20, by which the heating fluid may be supplied and condensate removed continuously.

45 The evaporator consists of a closed shell or

body 10 adapted to contain a quantity of aqueous solution to be treated, and is provided at its lower end with an inverted conical section 21 to which the upper end of the pipe 13 is connected. Openings 22 and 23 are provided at the upper end of the body 10 and at the lower end of conical section 21, respectively, for the release of steam and the discharge of crystals. The opening 22 may be connected with a condenser (not shown) or with the succeeding body of a multiple effect evaporator (not shown). Disposed concentrically within the conical lower end of the evaporator body is a like-shaped sleeve-like partition or conical member forming a chamber or separator 24 which is open at the top and defining or constituting a substantially annular partition which is spaced from the walls thereof to provide an annular space or passage 25 for the circulation of the solution, and disposed at the lower end of the separator in communication with the pipe 14 is a distributor indicated generally by the numeral 26 which functions, in conjunction with the conical separator, to divide the flow of solution from pipe 14 into numerous thin sheets which issue at a predetermined velocity upwardly into the solution contained in said separator in the manner which will hereinafter appear.

The distributor is substantially hollow or skeleton-like in form and is so designed as to effect the circulation of the heated solution from the pipe 14 as well as from the passage 25 into the conical chamber 24, the latter separating the ascending current of solution inside the chamber from the descending current exteriorly thereof. To this end, this distributor consists of a central spreader 27 in the form of an inverted cone which preferably terminates at its lower end immediately above the open end of pipe 14, and extending from this spreader are hollow, thin walled radial arms or spokes 28 which may be permanently secured in any appropriate manner to the upper end of such pipe 14. These arms merge at their upper ends into the top side of the conical spreader to provide intervening spaces or ports 29, and their inner edges are substantially upright and coextensive with the inner wall of the pipe 14, while their closed bottom edges may be inclined outwardly to merge into the contiguous wall of the conical chamber 24. Formed in the arms 28 are slots 30 which converge upwardly and through which the heated solution is circulated upwardly and discharged in thin sheets from the pipe 14 into the chamber 24, while the solution contained in the evaporator body is circulated downwardly through the passage 25 and thence upwardly through the spaces 29 between the slotted arms. The solution issues from the slots at such a velocity that part of its energy is imparted to the solution into which it issues, thus causing circulation of solution upward through the ports 29 and inner cone 24 and its return downward through the annular space 25. There is also a thorough commingling of the heated solution from the slots with the cooler solution contained in the evaporator. The upper end of the chamber 24 is open and preferably disposed below the normal level of the solution, as indicated in Figure 1. It will also be noted in this figure that the spreader forms a closure for the top of the pipe 14 to divert the ascending current of solution into the hollow arms 28.

The apparatus is so proportioned that the solution covers the top of the distributor 26 to such

depth that boiling does not occur until after the heated solution has mixed with the cooler solution and ascended in the inner conical chamber 24 to a zone nearer the surface. The circulation is assisted by the difference in weight between the mixture of solution and steam enclosed by such inner chamber and the solution in the annular space 25. The apparatus is also so proportioned that the combined area of the ports 29 is greater than the combined area of the discharge ends 10 of the arm-slots.

In the operation of the apparatus, the solution to be treated is continuously supplied to evaporator 10, at the rate required to maintain the desired level. Pump 12 is operated continuously, and the solution is drawn through pipe 13, forced through heater tubes 16 and return pipe 14 and discharged into the body of liquid in the evaporator through slots 30. As the solution passes through the tubes 16 it is heated by the steam or other heating medium in the chamber 15 and enters the evaporator 10 at a temperature several degrees above the temperature of the solution contained in the evaporator, which has a temperature corresponding to the boiling point of such a solution at the absolute pressure maintained in the evaporator.

The temperature increase of the solution passing through heater tubes 16 is derived from the temperature difference between the heating medium surrounding the heater tubes 16 and that of the liquid in the tubes. The higher temperature of the heating medium may be obtained in various ways. When steam is used it will be at a pressure higher than the pressure in evaporator 10.

To insure the maintenance of the desired temperature difference and rate of heat transfer, accumulation of condensate and/or gases in the heated shell 11 is prevented by their removal through outlet 20.

After being heated in the tubes 16, the solution passes through pipe 14 into the interior of the evaporator 10, issuing in thin sheets from the slots 30 and entraining liquid from the body of solution in the inner cone 24, which entrained liquid moves upwardly and is replaced by liquid flowing through the passages or ports 29. The conical chamber 24 separates the ascending current of solution from the current descending through the intervening passage 25. The circulation thus produced is accelerated by the formation of steam bubbles within the conical chamber 24 and the consequent unbalancing of the ascending and descending columns of liquid.

Since the heated solution supplied by pipe 14 mixes with a much larger volume of cooler or relatively unheated solution within the evaporator 10, the temperature of the mixture is much lower than that of the heated solution alone and violent boiling is thus avoided. No boiling or ebullition occurs until the heated solution rises to a level where the hydrostatic head is reduced to a value which will permit boiling under the existing temperature and pressure conditions, and at this level the boiling which occurs is distributed over the entire area within the conical chamber 24 and is quiet and uniform and out of contact with the shell of the evaporator. As a consequence, there is no accumulation of crystals on the surface of the evaporator shell. Similarly, there is an absence of deposit in the heater tubes because the solution is in continual circulation, enters the heater tubes at saturation,

and increases in temperature as it passes through but does not boil in the tubes.

By reason of the continual circulation of the solution in the evaporator, crystals thrown out of solution are repeatedly carried upwardly through the chamber 24 until they attain a size that causes them to settle into the bottom of the evaporator from which they may be removed through opening 23 in the usual manner, continuously or otherwise. Suitable connections may be provided for supplying additional solution to replace losses by evaporation and for the removal of crystals.

Any suitable means may be provided for effecting the removal of crystals and the replacement of solution to maintain the desired level in the evaporator, and continuously or intermittently operating means may be employed for these purposes, such means being well known and forming no part of my invention.

The continual circulation and repeated passage of crystals through the zone in which material is thrown out of solution by evaporation is favorable to the building up of crystals of large size. The power required for circulation in the system is a minimum, the system being hydrostatically balanced and requiring only sufficient power to overcome friction. Furthermore, by my construction of evaporator, the circulation is such as to carry the crystals around and around so that crystals of large size can be produced and the operation is quiet and regular and can be operated for long periods without interruption.

25 I claim as my invention:

1. An evaporator comprising a casing adapted to contain liquid, said casing being divided to provide intercommunicating main and secondary circulating chambers, a pipe for supplying liquid to the main chamber of said casing, said pipe having its discharge end spaced from the walls of said casing and formed with spaced radially disposed arms provided with slots therein for the issuance of liquid therefrom in spaced streams 40 into said main circulating chamber, the spaces between said arms constituting passages establishing communication between the lower ends of said main and secondary chambers.

2. An evaporator, comprising a container for liquid through said separator member, and lower portion of said container in spaced relation to its surrounding wall to provide a down-circulating passage for the liquid and opening at its upper and lower ends into said container 55 for providing for the upward circulation of the liquid through said separator member, and means for supplying heated liquid directly into the lower end of said separator member and for causing the entrainment therewith of liquid 60 within the container to effect a circulation of such liquid upwardly through said separator member and downwardly through said surrounding circulating passage, said means including a slotted portion for discharging the heated liquid 65 in thin sheets upwardly into the interior of said separator member and an intervening ported portion for establishing induced circulation through the down-circulating passage and upwardly through said separator member.

70 3. An evaporator, comprising a container for liquid having a concentrically arranged, partition-like wall therein defining a main chamber for the upward circulation of liquid and an annular secondary passage for the downward circulation of the liquid, means for supplying heated

liquid to the container, and a distributor connected to the lower end of said partition-like wall and having a discharge in communication with said liquid-supplying means for introducing the heated liquid directly into said main chamber, said distributor having ports therein adjacent its discharge for establishing induced circulation of the liquid downwardly through said secondary passage and thence upwardly into the main chamber.

4. An evaporator, comprising a container for liquid having a concentrically arranged, partition-like wall therein defining a main chamber for the upward circulation of liquid and an annular secondary passage for the downward circulation of the liquid, means for supplying heated liquid to the container, and a distributor connected to the lower end of said partition-like wall and having a plurality of discharge ports therein establishing communication between said liquid supply means and said main chamber, said distributor having intervening ports between said discharge ports for establishing communication between the lower ends of the main circulating chamber and the secondary circulation passage.

5. An evaporator of the character described, comprising a container for liquid having its lower portion substantially cone-shaped, a pipe for supplying liquid to the container, the discharge end of said pipe being located within the cone-shaped portion of said container, a substantially cone-shaped partition disposed concentrically within the like-shaped portion of said container and defining a main chamber for the upward circulation of the liquid and an annular secondary passage for the downward circulation of the liquid, and a distributor means interposed between the discharge end of said pipe and the opposing lower end of said conical partition, said distributor means having a plurality of ports therein for introducing the fluid in stream-like fashion from said pipe into said main circulating chamber and having intervening spaces between said ports for establishing induced down circulation of the fluid from said secondary passage into said main chamber.

6. An evaporator, comprising a container for the liquid, a substantially sleeve-like partition disposed in said container with its top edge below the level of the liquid therein and spaced from the container wall for defining an inner chamber for upward circulation of liquid and an annular outer chamber for downward circulation of liquid, a pipe for conveying heated liquid to said container and having its discharge end in communication with said inner chamber, and a distributor at the discharge end of said pipe having ports and deflecting means for directing the heated liquid in thin sheets into the lower portion of the upward circulation chamber and having passages adjoining said ports for establishing induced circulation between the lower portions of said inner and outer circulating chambers.

7. An evaporator, comprising a container for liquid having means therein below the liquid-level for defining an inner chamber for the upward circulation of the liquid and an outer chamber for the downward circulation of the liquid, a heater for heating the liquid, a pump interposed between the container and the heater including pipes for circulating the liquid from the container through the heater and returning it from the heater to the inner, upward circulation chamber of said container, and means interposed

between the discharge end of the return-circulating pipe and said chamber-defining means for controlling the flow of heated liquid from said return pipe into said inner chamber and for controlling induced circulation of the fluid in said container, said means including ports for directing the heated liquid in thin sheets into the lower end of said upward circulation chamber and other ports disposed in cooperative relation to said

5 first-named ports for establishing communication between the lower ends of said downward and upward circulation chambers.

8. An evaporator, comprising a container including means therein dividing it into substantially concentrically-disposed, circulating chambers for the upward and downward circulation of the liquid in a predetermined zone, a pipe for conveying heated liquid to said container, and a distributor disposed between the discharge end 15 of said pipe and said chamber-forming means including a member having a plurality of spaced hollow arms opening at their lower ends into the discharge end of said pipe and at their upper

ends into the lower end of said upward-circulating chamber, the spaces between said arms providing for the circulation of the fluid from the lower end of the downward circulating chamber to the companion end of the upward circulating 5 chamber.

9. An evaporator, comprising a container for the liquid having means therein defining a predetermined circulating zone, a pipe for supplying liquid under pressure to said circulating zone 10 and means for heating the liquid in said pipe, the discharge end of said pipe being provided with a distributor head having radially-spaced, slotted arms for issuance of heated liquid therefrom into said circulating zone and the resulting 15 spaces between said arms establishing communication between the interior and exterior of the circulating zone-defining means for causing the entrainment, with the heated liquid, of liquid within the container to effect mixture and circulation of the heated liquid and the body of liquid in said container.

BURTON S. HUGHES.

CERTIFICATE OF CORRECTION.

Patent No. 2,207,347.

July 9, 1940.

BURTON S. HUGHES.

It is hereby certified that error appears in the printed specification of the above numbered patent requiring correction as follows: Page 3, first column, line 50, claim 2, strike out the words "liquid through said separator member, and" and insert instead --liquid, a separator member disposed within the--; and that the said Letters Patent should be read with this correction therein that the same may conform to the record of the case in the Patent Office.

Signed and sealed this 27th day of August, A. D. 1940.

(Seal)

Henry Van Arsdale,
Acting Commissioner of Patents.
